FLASHLIGHT

Gwilym F. Prideaux, Cleveland Heights, Ohio, assignor to General Electric Company, a corporation of New York

Application June 10, 1942, Serial No. 446,513

1 Claim. (Cl. 240—10.68)

My invention relates to electric lamps of the portable, self-contained, battery operated type commonly known as flashlights. The principal object of my invention is to provide a flashlight comprising an incandescent lamp and automatic means for interrupting the circuit including said lamp in predetermined positions of said flashlight. Another object of my invention is to provide a flashlight comprising an incandescent lamp and an automatic switch constructed and arranged to so control the circuit including said lamp that the flashlight is capable of emitting light in a selected angular path upward or downward 90° from the horizontal and is incapable of emitting light in the angular path opposite to that selected. A further object of my invention is to provide a flashlight adapted to project light in a horizontal direction or below the horizontal only.

Further objects and advantages of my invention will appear from the following detailed description of species thereof and from the accompanying drawing, in which Fig. 1 is a side elevational, schematic, partly sectional view of a species of flashlight embodying my invention; Fig. 2 is a sectional view taken along the longitudinal axis of a species of switch useful for the purposes of the invention in the flashlight shown in Fig. 1 and showing the switch in a contact making position; and Fig. 3 is a similar view of the switch in a contact breaking position.

Referring to Fig. 1 of the drawing, the flashlight 10 comprises a tubular, electrically insulating, plastic casing 11 closed at one end and having a screw cap 12 at the open end thereof. A fluid flow switch 13 and a conventional flashlight battery 14 are disposed in said casing 11. The switch 13, which contains mercury or an equivalent material, is provided with an electrical conductor in the form of a metal strip 15, the end of which is disposed between the switch 13 and the closed end of said casing 11. Said strip 15 extends to the open end of said casing 11 where it is bent outward. Said screw cap 12 encloses a metal washer 16 adapted to screw onto the screw base 17 of the incandescent lamp 18. A spring 19 is compressed between said washer 16 and the battery 14 and is spaced from the central terminal 20 of the battery 14. The force exerted by said spring 19 is sufficient to hold the rim of the washer 16 firmly against the cap 12 and to press the battery 14, the switch 13, and the end of strip 15 together. The circuit including the battery 14 and the lamp 18, which is shown as broken in Fig. 1, is made by turning the screw

cap 12 in the proper direction to further compress the spring 19. The washer 16 is thus brought into contact with the end of strip 15 and the center contact of the lamp base 17 into engagement with the center terminal 20 of the battery 14. The washer 16 may be flexible to facilitate this operation and to avoid the necessity for close tolerances of the engaging parts. The lamp circuit is broken by turning the cap 12 in the opposite direction to permit expansion of the spring 19 which forces the washer 16 and the center contact of the lamp base 17 away from the terminal 20 and the end of strip 15, respectively.

The cap 12 is provided with a window 21 which transmits the light emitted by the lamp 18. The window 21 may consist of material capable of transmitting all of the light emitted by the lamp 18 or of screening out all but a selected part of the light. Thus, blue, orange, or red screens or filters may be used. The rim portion or flange 22 of cap 12 is of larger diameter than that of the tubular casing 11 so that the longitudinal axis of said flashlight is directed or tilted upward from the horizontal with the lamp end higher than the opposite end thereof when the flashlight is placed upon a substantially horizontal surface, such as a floor, or a table.

The mercury switch 13 is constructed and arranged to automatically interrupt the lamp circuit when the lamp end of the flashlight is higher than the opposite end thereof. Thus the flashlight comprises manually controlled means for making and breaking the lamp circuit in any position of the flashlight and automatically operating means for making the lamp circuit when the lamp supporting end of the flashlight is pointed downward and for breaking the lamp circuit when said lamp supporting end is directed upward. Thus, the light from the flashlight cannot be inadvertently directed upward. This is advantageously in many locations, such as in theaters, where an upwardly directed light source in the hands of an usher, for example, is not desirable.

A species of mercury switch useful in the flashlight illustrated in Fig. 1 is shown in Fig. 2 in a circuit making position and in Fig. 3 in a circuit breaking position. The switch 13 is tubular in shape and is mounted with its longitudinal axis coincident with or parallel to the longitudinal axis of the flashlight 10. Said switch 13 comprises two metal contact members 23 and 24 joined in spaced relation by a tubular sleeve 25 of electrically insulating material to form an enclosure for a drop of mercury 26, or equivalent material. The contact member 23 is hollow to

provide space for the movement of the mercury 26 and terminates in the sleeve 25 a slight distance from the slightly rounded part of the solid contact 24 in said sleeve 25. The drop of mercury 26 is sufficient in size to bridge the gap between the contacts 23 and 24 when the longitudinal axis of the switch is vertical and the contact 24 is in the lowest position. The mercury 26 also bridges this gap as the axis of the switch 13 is moved from a vertical to a horizontal position. When the switch axis is tilted further to raise the contact 24 above the contact 23 the drop of mercury 26 moves toward the end of the contact 23 remote from the contact 24, as shown in Fig. 3, to break the electrically conducting path in the switch 13.

As pointed out above, the switch 13 is mounted with its longitudinal axis parallel to or coincident with the longitudinal axis of the flashlight. In so mounting said switch 13 the contact 24 should be closer to the lamp end of the flashlight than the contact 23 when automatic interruption of the lamp circuit by the switch 13 on pointing the lamp end of the flashlight above the horizontal is desired. Of course, the position of the contacts is reversed when the flashlight is desired for emitting light upwardly only.

While I have shown and described a specific form of flashlight and mercury switch, it will be understood that I contemplate that other types of flashlights and switches may be used without departing from my invention. For example, my invention may be used in flashlights comprising a manually operated switch distinct from the cap 12. It is also useful in connection with commercial flashlights incorporating a reflector to collect and project the light from the lamp 18 in a beam, the axis of which may be coincident with

or normal to that of the battery enclosing casing. In mounting the switch 13 in such flashlights, the longitudinal axis thereof is coincident with or parallel to the beam axis. The switch may be interposed between the central terminal of the battery and the center contact of the lamp base in flashlights similar to that shown in Fig. 1. This arrangement is preferred in flashlights projecting a beam having its axis normal to that of the battery case.

What I claim as new and desire to secure by Letters Patent of the United States is:

A portable flashlight comprising a cylindrical casing having an open front end, a battery in said casing, an opaque outwardly rounded cap mounted on the open end of said casing so as to be movable relative to the casing and having a small window at the center thereof, a lamp at the open end of the casing, connections for completing an electric circuit from the battery through the lamp, means to support the lamp from the cap, spring means arranged to hold the lamp in open circuit position, and gravity-operated switch means in the electric circuit, said switch means being tubular, of uniform bore and disposed with its longitudinal axis coincident with that of the casing so as to open the circuit only when the flashlight is pointed above the horizontal, the said cap serving to move the lamp into closed circuit position when the cap is moved relative to the casing and also having a periphery of larger diameter than the casing which serves to point the flashlight above the horizontal, when it is set on a horizontal surface, and thereby move the gravity-controlled switch to open position.

GWILYM F. PRIDEAUX.
